UNITED STATES PATENT OFFICE.

THOMAS E. ROBINSON, OF PHILADELPHIA, PENNSYLVANIA.

GATE OR DOOR OPERATING MECHANISM.

Application filed January 17, 1924. Serial No. 686,736.

My invention relates to sliding gates, with particular reference to gates and doors into freight elevator shafts.

The purpose of my invention is to provide 5 a novel form of sliding gate that is particularly well adapted to meet the needs of service; a gate that will easily open, automatically stay open to any desired extent while the elevator is at the gate, that will 10 gently and automatically close to any predetermined extent when the elevator moves from the gate, and that will be held in closed position at other times, as by its own weight, even when, as I prefer, it is not locked 15 closed.

A further purpose is to render the counter-weighting ineffective when the elevator is not in position at the floor protected by the gate to provide for automatic closing and 20 difficult opening then.

A further purpose is to counterweight different ends of a telescoping gate upon different leverages and to limit the telescopic opening of the door.

25 A further purpose is during closure to gradually transfer part of the effective pull of the gate upon the counterweight from a larger to a smaller leverage so as to automatically stop the gate by increasing (preferably progressively increasing) the counter-weighting of an initially under-counter-weighted gate.

30 A further purpose is to provide for gentleness of automatic closure by increasing the effect of the counterweighting as the gate approaches its position of closure.

A further purpose is to have the counter-weighting connection ratcheted during automatic closure of the gate when the elevator 35 is not at the floor protected by the gate so as to prevent any rebound of the gate from its position of closure, changing the under-counterweighting as the gate approaches its position of closure to over-counterweighting for rapid yet gentle deceleration to closure.

40 A further purpose is to provide means effective when the elevator is not at the gate whereby the shaft is locked from turning in opening direction and free to turn in closing direction, permitting the gate to gently automatically close when the elevator 45 leaves the gate and then to be held shut by the entire pull toward closure.

A further purpose is to provide a sliding

gate normally tending to close and counter-weighted, with selective means, controlled by the position of the elevator, for stopping closure or checking opening movement of the counterweight. 55

A further purpose is to provide a constant 60 pull of the gate toward closure (as by its own or other weight) and to partially counterbalance this pull when the elevator is at the gate to permit easy opening with latch (preferably ratchet) holding of the gate in 65 open (preferably progressively opening) positions.

A further purpose is to apply the normal 70 pull of the gate toward closure and a partially balancing, oppositely counterweighting pull to a rotary shaft controlled directly or indirectly by ratchets so as to check movement due to the normal pull when the elevator is at the gate, holding the gate in any 75 position to which it has been raised, and to release the gate and to make the pull of the counterweighting upon the gate ineffective to help opening movement of the gate when the elevator is not at the gate, so that the 80 normal pull of the gate will close it and the absence of counterweighting will make it difficult to open.

A further purpose is to apply the normal 85 closing pull of a gate toward rotation of a shaft, and the counterweighting for the gate toward the rotation of a shaft, preferably the opposite rotation of the same shaft, and to stop either rotation by ratchets (in the preferred form oppositely facing ratchets on the same shaft) and to determine which 90 ratchet shall be operative by the position of the elevator.

A further purpose is to provide an advantageous and novel ratchet and pulley mechanism upon a counterbalancing shaft 95 for an elevator gate.

A further purpose is to use variant leverages in the same sprocket wheel.

Further purposes will appear in the specification and in the claims. 100

My invention relates to methods involved as well as to the apparatus used.

In the drawings I have shown a few only of many forms embodying my invention, selecting forms which are practical and effective, but particularly because they well illustrate the principles involved. 105

Figure 1 is a front elevation of a verti-

cally sliding collapsible gate in position of closure somewhat above the floor line, the frame being sectioned in correspondence with line 1—1 of Figure 2.

5 Figure 2 is a section upon line 2—2 of Figure 1, a part of the guide box being eliminated so as to show the gate.

10 Figure 2^a is a fragmentary section corresponding to Figure 2 but showing a second form.

Figure 3 is a view corresponding to Figure 1 but with the gate open.

15 Figure 4 is an enlarged detail from Figure 1, showing operating mechanism, but for the sake of clearness omitting the sprocket chain and counterweight, the parts being shown in position when the elevator is not at the floor.

20 Figure 5 is a section of Figure 4 taken upon the line 5—5.

Figures 6 and 7 are somewhat diagrammatic front elevations of modified forms.

25 Figure 7^a is a fragmentary front elevation of another form.

29 Figure 8 is an enlarged detail from Figure 7.

30 Figure 8^a is a section, in slightly different position from that in Figure 8, of the structure seen in Figure 7^a.

35 Figure 9 is a section of Figure 8 taken upon the line 9—9.

Figure 10 shows diagrammatically another form.

35 In all figures like numerals refer to like parts.

Describing in illustration and not in limitation and referring to the drawings,—

40 My invention finds its widest application in use with freight elevator gates safe-guarding the elevator shaft while the fire doors are open and the elevator car away.

45 Whenever there is not ample head room for a vertically sliding gate it is desirable to have the gate collapsible so as to occupy very little vertical height when in raised position and the gate shown in Figures 1—5 is of this type. While I have illustrated the main form as of the collapsible type, it is to be understood that many features of the invention are equally applicable to gates that do not collapse and to doors for many purposes other than the elevator shaft use suggested. The word "gate" as used herein is intended generally to apply also to doors wherever its setting permits such generic use. In special cases, where there is plenty of head room, there may be no particular advantage in having the gate collapsible, and I illustrate the invention diagrammatically operating non-collapsible gates in Figures 7 and 10.

55 The collapsible gate 15, illustrated in Figures 1—3, slides vertically in guiding runways 16 at opposite sides of the elevator opening 17. The floor-line, wall adjacent

the elevator shaft, and "toe-board" at the top of the opening are shown, respectively, at 18, 19 and 20.

59 The gate is formed of strips 21 collapsibly latticed upon pivot pins 22 and 23, similarly to lazy tongs and stopped from extension beyond the limit shown in Figure 1 by means of lateral co-operating links 24 and 25, a suitable stop 26 on each pair of links 24, 25 limiting the relative angular spread 65 of the lattice work. The precise way of limiting the extension of the lattice is obviously not material. Where lateral links 24, 25 are used, their extreme spread should be very materially less than 180° to insure easy 70 closure.

75 The operating and control mechanism of the gate is duplicated upon opposite sides so that it will be sufficient to describe one side, the same description applying to both 75 sides.

80 The double sprocket wheel 27 is pivotally mounted in the upper framework of the doorway upon a shaft 28 and by means of chain 29 and counterweight 30 supports and 75 positions the gate.

85 The double sprocket wheel comprises 85 wheels 31 and 32 of different diameters, preferably formed as two separate castings and locked from relative turning in any convenient way, such as by longitudinally interlocking hubs seen at 33 and 34 in Figure 5. The separate castings permit interfitting and use of different proportions or sizes 90 of sprocket wheels to suit the requirements of different sizes, weights and arrangements 95 of doors, and without changing ratchet dimensions.

95 The gate being collapsible, the top of the gate does not have as large range of travel 105 as the bottom, and this is taken care of by having the supporting chain 35 from the smaller wheel fastened to the top of the gate and the supporting chain 36 from the larger wheel fastened to the bottom of the gate. I 110 have had great success with a ratio of speed 115 between the top and bottom of 1 to 2, using a gate whose extended height is just twice its height when collapsed, but of course recognize that this ratio need not be maintained, even with the form of collapsing 120 gate shown in Figure 1, as the ratio of full length and collapsed heights could be greatly varied and the gate need not be fully collapsed. In order to avoid the need for two 125 counterweights or for running one chain from the sprocket wheel without direct counterweighting, I prefer to use a single chain and to support a single counterweight 30 from a pulley 37 rolling upon the chain. The counterweight preferably operates 130 within a suitable guide box 38.

135 In order that the gate may not open easily when the elevator is not at the floor, I provide ratchet mechanism locking the double 130

sprocket wheel from turning in such direction as to open the gate during the period the elevator is not at the floor; with the intent and effect to neutralize the partial counterweighting of the weight 30. If the gate be now lifted, no benefit is secured from the counterweighting. If lifted from the top the entire weight must be lifted. If lifted from the bottom, the weight will not be that of the entire gate at the start, owing to inevitable lost motion, but as the lost motion is taken up the weight will increase progressively until the entire weight is being lifted. If released the entire weight lifted tends to drop the weight to its former position.

This mechanism comprises ratchet teeth 39 upon the radially extended rims 40 and 41 of the sprocket wheel 32 and pawl 42 loosely pivoted on rod 43. The lower end 44 of the pawl weights the pawl toward engagement with the ratchet. An operating mechanism shown as a cam, and preferably a push cam 45 carried by a sliding rod 46 is adapted to engage the toe 44 of the pawl 25 to hold the pawl from engagement with the ratchet. Normally the spring 47 (where the operating mechanism is the push cam) presses the rod 46 outwardly, permitting the pawl to engage the ratchet, but when the elevator is at the floor any suitable part of the car (not shown) engages the shoe 48 pressing it inwardly against the action of the spring 47 and holds the pawl away from its ratchet.

35 This ratchet mechanism serves not only to make it hard yet possible (by lifting the weight of the gate) to open the gate when the elevator is not at the door, receiving no help from the counterweighting, but allows 40 upward movement of the counterweight until balance is effected when the gate falls.

Other ratchet mechanism, operative when the elevator is at the gate and then only, prevents the double sprocket wheel normally 45 from turning in closing direction when the elevator is at the gate but permits the gate 50 to be opened and, when opened, to stay open automatically wherever set and, because of release of this ratchet, automatically closes 55 as the elevator leaves the gate. Where two pulleys (sprocket wheels) are used together, as is the case for collapsible gates, it is convenient to form ratchet teeth 49 for this second ratchet upon the radially extended 60 rims 50 and 51 of the sprocket wheel 31. Pawl 52 may also loosely pivot upon the same rod 43. The lower end 53 of the pawl weights the pawl toward engagement with its ratchet. The same operating device, here 65 push cam 45 on sliding rod 46, may engage the toe 53 of the pawl, holding it from engagement with its ratchet except when the car is at the gate.

In view of the desirability to standardize 65 as far as possible the parts of the equipment

and of the difference of the requirements in practice making desirable any one of a number of ratios between the effective diameters of the sprocket wheels without any variation in the ratchet mechanism, I 70 radially extend the rims 40, 41 and 50, 51 respectively of the sprocket wheels, and in this way am enabled to have room for variation in the ratio of the diameters of the sprockets without variation in the sizes of 75 the ratchets.

When the elevator is at the gate, the gate is free to open easily, being partially counterweighted. It will stay open wherever set, the pawl 52 engaging the ratchet 80 teeth 49 to prevent turning of the double sprocket wheel in closing direction.

During this operation the two ends of the gate are pulling upon different leverages corresponding to the radii of the two sprocket 85 wheels and the counterweight is operating upon corresponding leverages equal at each sprocket wheel to the leverage of the gate attachment. If there were no lost motion in the collapsible gate there would be approximately equal pull upon the gate attachments at top and bottom at all intermediate positions of the gate with a maintained ratio of lifting movement such that the complete collapse of the gate at the 90 top would bring all of the weight upon the lower attachment operating on the longer leverage and that the extreme bottom of the movement owing to the limitation of opening movement of the gate all of the weight 100 would be taken immediately upon the upper attachment operating about the shorter leverage.

As the presence of lost motion is inevitable, however, starting from the position 105 seen in Figure 1 the collapsing proceeds somewhat more rapidly at the bottom than at the top with opening movement of the gate allowing a greater proportionate pull upon the attachments at the bottom of the gate. For the same reason when the case 110 has been completely collapsed at its upper position and starts downwardly, a relatively larger part of the weight is sustained by the attachments to the bottom of the gate 115 which disproportion is reduced as the gate approaches its lowermost position. When the gate reaches the point where the arms 24 and 25 lock against further opening and the chains 36 become slack because they are moving downwardly at a faster rate than the chains 35 without corresponding extension of the gate, the weight of the gate which has been divided between the two leverages 120 corresponding to the two leverages upon which the counterweight is operating is finally rested wholly upon the shorter leverage through chains 35 shifting from a condition of under-counterweighting to a condition of over-counterweighting. As a result 125 130

of this the counterweighting quickly brings the gate to rest without necessity for stops engaging the gate. The gate may thus be made to stop at any predetermined point above the floor. The distance which the gate will travel before stopping after the leverage exerted by it has been shifted from the divided leverage to the short leverage of the small pulley depends upon a number of factors including the amount of under-counterweighting and the amount of lost motion in the gate structure.

Since the latch 52 holds the gate in suspensions in any position which it has reached during upward travel while the elevator car is at the floor, the gate need not be completely raised to any catch and when the ratchet is released whether by reason of movement of the elevator car or separately the weight of the gate will cause it to close from the position to which it has been lifted. The latch 42 offers no resistance to this movement.

When the elevator car is not at the floor the latch 52 is released, but the latch 42 is in engagement with its ratchet preventing downward movement of the counterweight. As a result no benefit from the counterweighting is had in lifting the gate and the entire weight of the gate must be lifted in opening.

I preferably provide a safety buffer 54 between the counterweight and the operating mechanism. This buffer is merely a safety device and guard for the operating mechanism and normally will never be engaged by the counterweight. The gate is stopped not by engagement between the counterweight and buffer but by the rapid deceleration due to the shifting from under-counterweighting to over-counterweighting a little before the closing position has been reached. The closing position is normally about six inches from the floor. This capacity for coming to rest without striking a definite stop does not of course interfere with the use of the buffer as a stop or any other stop for the gate if desired.

In Figure 2^a separate chains are used and either of the chains, here 36, is not attached to the counterweight but is loose at the end nearest the counterweight. It passes over a sprocket 31² which is rotated by sprocket 32² and both of which are free from ratchet teeth. These are located at 49' and 39', respectively upon separate ratchet discs 31², 32² rotating with the sprockets. This construction, inferior to the other, is shown for the purpose merely of indicating that my broad combination is between the elements, so coupled as to operate at the same speed or selected ratio of speeds (preferably but not necessarily rigid with the same shaft) and preferably with a counterweight pulling upon both chains; but that for its broader

features my invention does not require the correlation of parts so desirable in my preferred form in the attainment of compactness, simplicity and cheapness.

The modified form shown in Figure 6 has precisely the same operating mechanism as in the first form, the only difference being in the form of collapsible gate, shown as comprising overlapping, oversliding gates 55 and 56.

The upper gate, 55, having a smaller range of travel is supported from the smaller sprocket wheel, and the lower gate, 56, having a wider range of travel, from the larger sprocket wheel. Any suitable stops 26' here shown as aligned ears, cause the upper gate section 55 to support the lower section at the limit the relative extension of the gates and result in gently bringing the gate to rest in automatic closure by throwing the entire support of both gates upon the chain 35, effectively changing the degree of counterweighting from under-counterweighting to over-counterweighting. A spiral spring 26² affords a resilient buffer between the parts, making the shifting of the counterweighting gradual.

Evidently some of the features of my invention are of general application and are separately available even where other features are not applied. Such, for example, are the locking of the counterweighting so as to eliminate the counterweight as an assistant in lifting the gate, whether the locking be controlled by automatic means or not; the automatic shift from latching the gate in its raised position to latching the counterweight, and vice versa, whether the latching of gate and counterweight be progressive or require a certain predetermined and reasonable full movement for the latching to be effective; and the shifting of the counterweighting from under-counterweighting to over-counterweighting.

The suitability of the first two of these for general use is obvious enough not to require illustration. I have thought it best, however, to illustrate another mechanism for accomplishing the shift in counterweighting in order that its further applicability may be made more clear.

Though my invention finds its best application in conjunction with collapsible gates, sprocket wheels of different size to cause travel at different rates and stop mechanism to limit the extension so all of the weight comes upon the top of the gate, making the shift in counterweighting to the best advantage on the gate side of the pulley (sprocket) support, the same general principle can be applied to doors which are not collapsible and the illustration in Figures 7-9 is intended to show this as well as to show the fact that the leverage of the gate upon the counterweight may be reduced or the lever-

age of the counterweight upon the gate may be increased at will to secure the results sought.

The method of counterweight shifting shown in Figures 7, 8 and 9 and in Figures 7^a and 8^a is not confined to use in conjunction with ratchet gate structures but can be used to accentuate the differences in leverage with collapsible gates.

In Figures 7-9 a non-collapsible gate 55' is shown, which may prove preferable on account of its low cost where the "head" room is ample.

The sprocket wheel member 27' has its sprocket teeth arranged in the form of a cam sprocket thread 57 upon which the chain 36' winds at one end as it unwinds at the other. This thread "deepens" to a shorter radius position 58 when the gate is nearly in its closed position on the gate side thereby lessening the arm of the turning moment exerted by the gate and increasing the counterbalancing effect of the weight, resulting as before in gentle closure. The ratchet mechanism is virtually the same as in the preceding forms except that the sprocket member is shown as an integral casting and the ratchet members 60 at opposite sides thereof are shown as of the same size with teeth 61 like ordinary gear teeth.

In Figures 7^a and 8^a the path 57 of the chain instead of being more deeply grooved at 58 upon the side finally engaged by the portion 36' of the supporting chain, to reduce the final leverage of the gate is given a larger leverage 58' at an intermediate point from which the portion 29 of the chain stretches to the counterweight so as to increase the leverage of the counterweight at this time when the gate is down obtaining the same relative effect of shifting the counterweighting from under-counterweighting to over-counterweighting.

In all of the preceding forms the weights of the gates supply a resilient force normally pulling the gates toward closure, adapting them to automatic closure when desired, ordinarily when an elevator car leaves the floor, and to gently come to rest at closure by means of an initial under-counterweighting increased to over-counterweighting at or near closure.

Usually it is advantageous to have the gates slide vertically, as in the preceding forms, making the weight of the gate normally thus available, as shown in the preceding forms.

In special cases, however, it is desirable to have a horizontally sliding gate or gates; in which case means normally pulling the gate toward closure must be added, as illustrated in Figure 10.

In Figure 10 is shown a pair of gates, 62 and 63 respectively, in position of closure.

Each gate is independent in its action, except as each may press against the other in closed position, and a single gate could be used. Where two are used the gates open and close oppositely with respect to one another and are shown provided with supporting rollers 64, traveling on track 65. They operate identically the same, so that only one need be described.

The weight 66 acts in the same way as gravity, exerting a constant closing pull through flexible connection 67 passing over pulley to a lug 69 upon the gate. The counterweight 30 operates through chain 29 passing over the sprocket wheel member 27' to under-counterweight the pull toward closure while the elevator is at the door, during opening of the door and during automatic closure until near closure when the under-counterweighting is automatically changed to over-counterweighting by a shift in the leverages at which the constant pull and counterweight operate to give gentle closure. The shift is accomplished here as in Figures 7, 8 and 9.

It will be obvious that in all of the forms shown and in order to get the full benefit of my invention there is the combination of a door pulling toward closure to effect automatic closure when the elevator leaves the floor, a partial counterweighting of the pull when the elevator is at the floor to permit easy opening and gentle closure, a material increase of the effective counterweighting near closure to make the closure much more gentle, ratchet mechanism making the counterweighting inoperative to assist in opening (but not inoperative to oppose further closing movement) except when the door is closing or the elevator is at the gate thus making it hard but possible to open the gate when the elevator is not at the gate, and other ratchet mechanism latching against closure when the elevator is at the gate and inoperative at other times, adapting the door to stay open at any position at which it may be set when the elevator is at the door.

In view of my invention and disclosure variations and modifications to meet individual whim or particular need will doubtless become evident to others skilled in the art, and I claim all such in so far as they fall within the reasonable spirit and scope of my invention.

Having thus described my invention, what I claim as new and desire to secure by Letters Patent is:

1. The method of counterbalancing a collapsible gate having a tendency to move to one direction, which consists in counterbalancing the gate at different points upon different leverages and shifting the pulls upon the two leverages so as to under counterweight at the start of closing movement and

to relatively increase the effect of the counterweighting against the gate pull in final closing movement of the gate.

2. The method of counterweighting a collapsible gate having a resilient pull toward closed position which consists in counterweighting the forward end of the gate considered in closing movement about a longer leverage than the rear end of the gate considered with the same direction of movement, selecting the counterweight to under counterweight when the gate is wholly or in part collapsed and part of the counterweighting pull is being taken by the forward end of the gate and to overbalance the counterweight as compared with the pull of the gate when the collapsible gate approaches closed position.

3. The method of counterweighting a collapsible gate having a continuous pull toward closing position; which consists in counterweighting spaced portions of the gate about pulleys having different leverages, controlling the pulleys to operate them together, stopping the extension of the collapsible gate positively and selecting the counterweight to represent over-counterweighting when the gate is fully extended and is pulling on the smaller leverage very largely or wholly and under-counterweighted when the gate is partly collapsed and more of its weight is supported upon the larger leverage.

4. The method of operating a gate which consists in counterweighting the gate about pulleys, applying oppositely facing ratchet control to said pulleys, setting the ratchet to allow downward movement only of the gate and upward movement only of the counterweight when it is desired to prevent opening thereof, thus rendering the counterweighting ineffective to open the gate during this time, and releasing the control of the downward movement of the counterweight when it is intended to open the gate.

5. The method of operating a gate which consists in counterweighting the gate about pulleys, applying oppositely facing ratchet control to said pulleys, setting the ratchet to allow downward movement only of the gate and upward movement only of the counterweight when it is desired to prevent opening thereof, thus rendering the counterweighting ineffective to open the gate during this time, and releasing the control of the downward movement of the counterweight and controlling the gate against downward movement thereof when it is intended to open the gate.

6. The method of controlling an elevator gate adapted to drop into closing position which consists in supporting it by counterweighting adapted to permit it to fall to the closed position, controlling the counterweighting by ratchet movement in opposite directions and utilizing the elevator car to

apply the ratchet to render the counterweighting ineffective when the elevator car is not in position at the door and reversing the ratchet control to prevent downward movement of the gate in raised positions 70 of the gate when the elevator car is in position at the gate.

7. The method of counterbalancing a collapsible gate continuously pulled toward closing position which consists in limiting 75 the extension of the gate, counterbalancing the gate at opposite ends upon different leverages and shifting the leverage upon the counterbalance as the gate closes from divided pull at the two ends to a pull at 80 the end having smaller counterbalancing leverages so as to shift the counterweighting from a condition of undercounterweight when the gate is open to a condition of equalization of counterweighting or over-counter- 85 weighting when the gate is closed.

8. The method of counterweighting and operating a vertically movable collapsible gate, which consists in supporting the gate by counterbalancing the upper and lower 90 parts, the leverage upon the counterbalance of the connection to the upper part of the gate being shorter than that to the lower part of the gate and collapsing the gate at the same time that it is raised. 95

9. The method of operating a collapsible vertically movable gate, which consists in supporting the gate at the top and bottom by counterweighting and operating about interconnected pulleys, the counterweighting 100 for the upper part of the gate being smaller than that of the lower part of the gate and thus collapsing the gate as it is raised.

10. The method of operating a collapsible vertically movable gate, which consists in supporting the gate at the top and bottom by counterweighting and operating about interconnected pulleys, the counterweighting for the upper part of the gate being smaller than that of the lower part 110 of the gate and the counterweighting being less than the weight of the gate in the raised positions of the gate and ratcheting the pulleys to retain the gate in raised position.

11. The method of operating a collapsible 115 vertically movable gate which consists in supporting the gate at the top and bottom by counterweighting operating about interconnected pulleys, the counterweighting for the upper part of the gate being smaller 120 than that of the lower part of the gate and the counterweighting being effectively less than the weight of the gate in the raised positions of the gate, ratcheting the pulleys to retain the gate in raised position and 125 automatically releasing the ratchet as the car leaves the position in front of the gate.

12. The method of operating a collapsible vertically movable gate at an elevator shaft, which consists in supporting the gate at the 130

top and bottom by counterweighting operating about interconnected pulleys, the counterweighting for the upper part of the gate being smaller than that for the lower part 5 of the gate, and the counterweighting being effectively less than the weight of the gate in the raised positions of the gate, ratcheting the pulleys to retain the gate in raised position and latching the counterweighting 10 so as to render it ineffective when a car leaves the position opposite the gate.

13. The method of operating a collapsible vertically movable gate at an elevator shaft, which consists in supporting the gate at the 15 top and bottom by counterweighting operating about interconnected pulleys, the counterweighting for the upper part of the gate being smaller than that for the lower part of the gate and the counterweighting being effectively less than the weight of the gate 20 in the raised positions of the gate, ratcheting the pulleys to retain the gate in raised position, automatically releasing the ratchet as a car leaves the position in front of the 25 gate and ratcheting the counterweighting so as to render it ineffective when a car leaves the position opposite the gate.

14. The method of easing the closing of a collapsible gate continuously pulled 30 toward closing position, which consists in applying the counterweighting to the gate at different points movable with respect to each other during collapse and with different leverages and in shifting the leverage of one 35 of the parts while maintaining the leverage of the other so as to increase the counterweighting relative to the closing pull upon the gate during the closing movement.

15. The method of protecting against 40 opening of a counterweighted gate, which consists in holding the counterweight against operation to assist in opening the gate.

16. The method of easing the closure of a collapsible gate made up of movable sections, which consists in supporting the sections separately from counterweights having 45 different leverages of the sections upon the counterweighting and in causing an upper section to take up the weight of a lower section during closing movement to shift the relative leverage of the counterweighting.

17. In a closure for elevator openings, a gate pulling toward closure, a rotary ratchet and pawl against door closure, and 55 means rendering the ratchet and pawl inoperative when the elevator is not at the opening.

18. A gate pulling toward closure, a partial counterweighting of the pull, means for 60 increasing the counterweighting in closure to over-counterweight before the position of closure is reached and means for holding the gate against upward movement due to the over-counterweighting.

19. In elevator apparatus, a shaft adapted

to rotate, a vertical sliding gate, connections between the gate and the shaft whereby the weight of the gate tends to turn the shaft in one direction, means tending to turn the shaft in the other direction to partially balance the turning tendency of the gate, 70 ratchet means engaging parts rotatable with the shaft adapted to prevent the shaft from turning in said other direction when the elevator is not at the gate and an automatic release for the ratchet controlled by the position of the elevator.

20. In elevator apparatus, a shaft adapted to rotate, a vertically sliding gate, connections between the gate and the shaft whereby the weight of the gate tends to turn the shaft in one direction, means tending to turn the shaft in the other direction to under- 80 counterweight the gate, and ratchet means 85 engaging parts rotatable with the shaft adapted to prevent the shaft from turning in said first direction when the elevator is at the gate.

21. In elevator apparatus, a vertically sliding gate, an under-counterweight therefor, a shaft for the counterweight, means operated by the elevator for making the under-counterweight inoperative at desired 90 positions of the elevator, and ratchet means 95 engaging parts rotatable with the shaft inoperative when the elevator is not at the gate for holding the gate open.

22. In elevator apparatus, a shaft adapted to rotate, a vertically sliding gate, connections between the gate and the shaft whereby the shaft must raise the gate if it turn in one direction, means tending to turn the shaft in the other direction to under- 100 counterweight the gate, and ratchet means 105 locking the shaft from turning in direction to raise the gate when the elevator is not at the gate and locking the shaft from turning to close the gate when the elevator is at the gate.

23. In elevator apparatus, a sliding gate 110 pulling toward closure, a partial counterbalance therefor, a rotary ratchet movable with the gate to turn when the gate moves, a pawl therefor pressing toward ratchet engagement and operating means holding the pawl from ratchet engagement and adapted to be displaced by the elevator to permit engagement between the pawl and ratchet.

24. In a vertically sliding gate, a collapsible lattice, means for raising and lowering 120 the top, whereby the weight of the lattice holds it extended, and other means for raising and lowering the bottom.

25. A vertically sliding collapsible lattice, 125 and means for simultaneously raising or lowering the top and bottom thereof to relatively different distances.

26. A vertically sliding collapsible lattice gate, a shaft adapted to rotate, supporting 130 connections between the shaft and the top

and bottom respectively of the gate, tending to rotate the shaft to lower the gate, and an under-counterweight for the gate.

27. A vertically sliding collapsible lattice gate, a shaft adapted to rotate and a gate-operating flexible connection supported thereby and on one side separately carrying the top and bottom respectively of the gate and on the other side loosely supporting an under-counterweight for the gate.

28. A vertically sliding collapsible lattice gate, a shaft adapted to rotate, a pair of wheels of relatively different radius fastened thereon to rotate therewith, and a flexible connection over the wheels supporting the top and bottom respectively of the gate on one side and supporting upon their other side an undercounterweight for the gate.

29. A sliding collapsible lattice gate pulling toward closure and collapse, a shaft adapted to rotate, a pair of wheels of relatively different radius mounted on the shaft to rotate therewith, flexible connections from

one side of the wheels to the respective ends of the gate supporting the gate from collapse and closure, and an under-counterweight for the pull of the gate loosely carried by the flexible connection on the other side of the wheels and maintaining proper engagement between the wheels and connection.

30. In elevator apparatus, the combination of a gate pulling toward closure to effect automatic closure as the elevator leaves the floor, a partial counterweight for the pull, means for increasing the counterweighting near closure to make closure more gentle, ratchet mechanism making the counterweighting inoperative when the gate is not closing and when the elevator is not at the gate to make it hard to open the gate, and other ratchet mechanism latching progressively with opening movement and against closure when the elevator is at the gate and inoperative at other times.

THOMAS E. ROBINSON.
